UNITED STATES PATENT OFFICE.

EMIL G. KREBS, OF TILLAMOOK, OREGON.

WHEEL-SUPPORT ATTACHMENT FOR DRAG SAW.

Application filed May 11, 1920. Serial No. 380,539.

To all whom it may concern:

Be it known that I, EMIL G. KREBS, a citizen of the United States, and resident of Tillamook, Tillamook County, State of Oregon, have invented a new and useful Improvement in Wheel-Support Attachments for Drag Saws, of which the following is a specification.

My invention relates in general to the well known type of portable drag-saw in which the saw is operated by an engine carried by the frame of the same. As well known, drag-saws of this type are now being largely used due to the fact that they can be operated by one man, and are readily moved from place to place.

To facilitate the ready moving of these saws, the manufacturers make them as light as possible, but even the lightest allowable construction is of considerable weight.

The commercial type of this drag-saw is generally mounted on a rigid angular frame, the vertex of which constitutes the base of the frame and is adapted to rest on the ground or other rigid support, while the opposite spread end of the frame is supported on the log to be sawed. When the drag-saw is to be moved to another place, it was necessary to pick it up bodily and carry it to such place. Such task obviously involves more or less hard work.

Therefore one of the main objects of my invention is to provide a wheel support by which the moving of the saw from place to place is facilitated, and which eliminates the hard work.

Furthermore, I desire to make my attachment both simple and inexpensive.

I attain my object by means of the device shown in the accompanying drawings, in which:

Fig. 1 is a side elevation of a gasoline drag-saw equipped with my attachment, and on which it is mounted ready for being moved;

Fig. 2 is a perspective view of my wheel-support attachment; and

Fig. 3 is a plan view of my attachment.

In the drawings, *a* represents a portable gasoline drag-saw of the usual construction, in which *b* are the legs or sides of the angular frame, *c* is the engine, *d* the fly wheel, *e* the stroke-arm, and *f* the saw. The vertex of the angular sides of the frame is reinforced by a block *g* which forms a block or foot for the lower end of the frame of

the drag-saw to rest on when the saw is being worked.

Laterally projecting handle-bars *h* are usually provided on this type of saw, the same extending perpendicularly from the sides of the saw frame at its lower end for the convenience of the carrier of that end.

My attachment is fastened to the saw frame by the aid of these handle-bars. 65

The attachment comprises a U-shaped yoke or frame preferably forged of a round, more or less, resilient metal bar, and having parallel arms *i*, bent at an obtuse angle in a vertical plane and provided with ears *j* 70 at their free extremities, constituting bearings adapted to be fastened on said handle-bars *h* of the drag-saw frame.

The opposite end of the attachment frame, that is, the closed end of the U, is so formed 75 as to provide a transverse axle-portion *k* on which is mounted the truck-wheel *l*. The frame portions *i'* are bent at diverging angles as more clearly shown in Fig. 3, so as to hold the truck-wheel *l* centrally between the sides of the attachment-frame and thus prevent it from interfering therewith. And intermediate the length of the attachment-frame the sides thereof are provided offset portions *m* constituting shoulders located and adapted to bear against the underside of the sides *b* of the saw-frame and support the latter adjacent its lower end. Said shoulders *m* also serve to hold the attachment frame against lateral movement on the arms *h* of the saw-frame. 85 90

When the drag-saw is to be moved to another place, my attachment is arranged as shown in Fig. 1. The sides *b* of the drag-saw frame will then rest on the shoulder or offset portions *m* of the frame of my attachment, and thereby holding the truck-wheel *l* in fixed position relative to the saw frame. 95

When my attachment is arranged as shown in Fig. 1, the drag-saw may be trundled about like a wheel-barrow; the ends *b'* of the saw-frame *b* being seized like the handle bars of a wheel-barrow, and in this way balancing and guiding the drag-saw. 100

When the drag-saw is to be put to work again, the yoke and wheel are swung clockwise on the hand-hold bars *h*, so that my attachment will be so arranged as to be away from the under-side of the saw frame and permit the block *g* of the latter to rest on the ground. 110

Hence my attachment does not interfere

in the least with the working of the saw; but may readily be re-arranged to provide a wheel support for the drag-saw when the latter is to be moved to another location.

5 I claim:

In combination with a supporting frame of the character described, provided with lateral handle bars, a wheel supporting attachment comprising, a substantially U-shaped frame, the free ends of the sides of which are provided with eyes for securing

on said handle bars, the closed end of the sides being adapted to constitute a transverse axle portion, a wheel mounted on the latter, said sides being provided with offset portions constituting shoulders adapted to bear against and support said frame, said sides converging beyond said shoulders towards said axle portion to hold the wheel centrally between the sides. 15

EMIL G. KREBS.
